SAFETY SHIELD FOR A TEXTILE COMBING MACHINE

Philip B. Tarbox, Clemson, and Carey A. Glazener,
Easley, S.C., assignors to Maremont Corporation

Filed Jan. 18, 1973, Ser. No. 324,883

Term of patent 14 years

Int. Cl. D15—06

U.S. Cl. D92—15

The figure is a front elevational view of a safety shield for a textile combing machine showing our new design, the other side being identical thereto and the design being of nominal thickness.

We claim:

The ornamental design for a safety shield for a textile combing machine, as shown.
